APPARATUS FOR REGULATING AND DELIVERING PAPER STOCK TO PAPERMAKING MACHINES

Richard T. Lang, Heidenheim on the Brenz, Germany, assignor to J. M. Voith, Heidenheim on the Brenz, Germany, a copartnership composed of Walther Voith, Herman Voith, and Hanns Voith

Application December 15, 1938, Serial No. 245,965
In Germany December 16, 1937

2 Claims. (Cl. 92—46)

This invention relates to means for supplying paper pulp to the wire of paper-making machines. The invention also relates to closed pipeline stock supplies, using a stock pressure box like that shown in my prior application for Letters Patent of the United States, filed under Serial No. 179,881 on December 15, 1937.

In such closed pipe lines, contrary to the arrangements with open stock inlets, the stock has no opportunity to de-aerate. In the open stock inlets the pressure is regulated by increasing the hydrostatic head. This cannot be done with a closed stock pressure box. It is the object of this invention to solve this problem. It is especially necessary to maintain the outlet pressure constant, and avoid great changes in the stock consistency after it has once been regulated. It is also desirable that during the whole production the jet of the pulp discharged from the nozzle of the closed stock pressure box always has the same direction and meets the wire of the paper-making machine at the same place. Uniformity is also desirable since every change in the once-fixed conditions must lead to trouble and loss in the production. It is, therefore, of fundamental importance in the use of closed stock pressure boxes, that the fixed working conditions are maintained during the whole production process.

A further object of the invention is to provide a circuit for the flow of the stock in the event that anything happens to the paper-making machine and it is necessary to cut off the nozzle supply to the wire, this circuit enabling the stock to be continually passed therethrough under maintenance of substantially the same density so as to be ready to be supplied by the nozzle to the wire upon opening the valve supplying the stock to the nozzle, and so that the stock is then in substantially the same condition as it was prior to the interruption.

The invention also contemplates the combination of parts and their novel cooperation so as to endeavor to obtain irreproachable and perfectly uniform paper texture.

One embodiment of the invention is illustrated by way of example in the accompanying drawing which is a diagrammatic elevation view.

Underneath the wire part of the paper-making machine the white water collects in a reservoir S, provided for the purpose. From there the white water runs in a connecting pipe s₁, which can be closed by means of a regulating member s₂, with a suitable gradient, to the suction side p₁, of a pump p. Into the suction pipe p₁ of this pump p

is also introduced the pulp, adjusted to the correct quantity in the usual manner by means of pulp-regulating slide valves or quantity regulators, by a separate pulp pipe g. The pulp supply through the inlet pipe g is usually regulated by a regulating member of known construction, for instance a regulating slide valve g₂, but in case of need the inlet pipe may be shut off by means of a separate quick-closing slide valve g₁. The pump p mixes the pulp and the white water and delivers the mixture to the usual pulp cleaning appliances d, for instance strainers or the like. The delivery pipe p₂, leading to these cleaning appliances d may of course be branched and sub-divided according to the number of such appliances, while regulating members d₁, provided therein distribute the desired quantity of pulp to the individual cleaning appliances d. In the embodiment illustrated, strainers are indicated as the cleaning devices. It is obvious that any cleaning appliance of known kind can be employed at this place.

The strainer or strainers d pour their contents into a large collecting box e. The latter serves both for the satisfactory de-aerating of the pulp that is ready for the machine and also for the accommodation of a supply of pulp, so as to compensate in this way for minor fluctuations in the pulp. On the storage tank e there may be provided an adjustable overflow e₂. The excess pulp is then conveyed by a pipe e₃ to the white water-collecting tank S. This overflow e₂ only comes into operation when a float e₁, and regulating members influenced thereby, are not switched on or are disturbed. From the de-aerating and storage vessel e the pulp flows to an adjustably driven pump a, which feeds the stock inlet B. From the outlet of the reservoir e, on the way through the suction pipe a₁, the pump a and the delivery pipe a₂, to the pulp outlet point C between the lips, the pulp is guided into a closed pipe line, and is subject to the pressure produced by the pump a. For the allocation of the pulp to the admission apertures provided on the stock inlet B; the delivery pipe a₂ is here subdivided in the particular manner desired.

In the case described, both for the pressure pump a and for the mixing pump p, adjustable drives a₃, p₃ are provided. While the speed of revolution of the pressure pump a is controlled either by hand or by mechanical appliances from the bottom of the paper machine, the motor p₃ of the mixing pump p must be controlled by a regulating device of known kind, which automatically regulates the speed of revolution of

this pump p , by means of a float e_1 , in dependence upon the level of the pulp in the storage tank e .

When pump drives capable of being regulated are employed, the pulp-feeding and regulating system works in the following manner: With an unchanged lip aperture at the outflow spout C of the stock inlet B , and with constant dilution and constant specific gravity of the pulp ready for the machine, the pressure necessary in the stock inlet can be adjusted either in dependence upon the speed of the paper machine or independently thereof by selecting a definite speed of revolution and therefore a definite output of the pressure pump a . The regulating device fitted into the storage reservoir e and consisting of a float e_1 is for the purpose of keeping the pulp level in the strainers d and therefore the suction height of the pressure pump a to the same level by regulating the mixing pump p in order that the operating conditions for the pressure pump a may always remain unchanged. For the satisfactory working of the stock inlet B , it is absolutely essential that the speed of the pressure pump a , when once adjusted, should be kept quite constant. On this ground, even in connection with circuits that are found by experience to exhibit no great fluctuations of voltage or of frequency, the motor a_3 of the pressure pump a is equipped with an electrical quick-acting regulator for instance, which keeps the speed, when once adjusted, absolutely constant.

If the pressure pump a and the mixing pump p are not driven by motors that can be regulated, the by-pass pipes a_4 , p_4 , shown in dot-and-dash lines in the figure, must be provided, for the purpose of regulating the output of the pumps. The pumps work in this case at their full power, while the excess quantity of stock not needed on the machine is returned by the by-pass pipes a_4 , p_4 from the pressure pipes a_2 , p_2 to the suction pipes a_1 , p_1 . The adjusting of the requisite pressure in the stock inlet B is effected with this arrangement either in dependence upon the speed of the paper machine or independently thereof by regulating a by-pass slide valve a_5 associated with the pressure pump a . The maintenance of the level in the storage tank e is effected by means of a float e_1 , which acts upon a throttle valve p_5 in the by-pass pipe p_4 of the mixing pump p .

If the mixing and pressure pumps a and p are constructed as propeller pumps, it is also possible, by shifting the blades of the rotors when stationary, to adapt the output of the pumps to the production of the machine, so that the quantity of stock flowing back through the by-pass a_4 and p_4 for instance can be kept fairly small.

In order to enable the supply of pulp to the stock inlet B through the pressure pipe a_2 to be interrupted, which is very important at high working speeds, there is provided in the delivery pipe a_2 a special shut-off member f , such as a rotary valve. By adjusting this valve f the delivery pipe a_2 is directly connected by way of an emptying pipe f_1 with the collecting tank S for the white water. The pulp therefore no longer rises in the stock inlet B , but is circulated within the system. Simultaneously with the actuation of the rotary valve f in the pressure pipe a_2 , the quick-closing slide valve g_1 in the pulp inlet pipe g is closed, in order that the pulp ready for the machine and circulating in the system may not be enriched by further pulp. For the approximate maintenance of the conditions once adjusted in the pulp-feeding and regulating system,

upon actuation of the rotary valve f , there is provided, as closure of the emptying pipe f_1 , into the white water collecting tank S , a weight-loaded check valve f_2 .

Provision is made for all the regulating members of the pulp-feeding and regulating system, for instance g_1 , g_2 , d_1 , p_5 , a_5 , f and s_2 , to be readily accessible, and to be capable of being controlled in a simple manner from the paper machine floor.

By the stock inlet according to my application Serial No. 179,881, in conjunction with the pulp-feeding and regulating system according to my invention aforementioned, a paper of satisfactory and completely uniform texture is ensured even with high speed paper-making machines.

It is obvious that various changes and modifications may be made in the details of construction and design of the above specifically described embodiments of this invention without departing from the spirit thereof, such changes and modifications being restricted only by the scope of the following claims.

I claim:

1. In an apparatus for regulating and delivering paper stock to Fourdrinier paper-making machines having a wire, a stock pressure head box with a stock flow nozzle for supplying stock to the wire, and a stock supply pipe having one end thereof connected with the stock pressure head box, the combination with said head box pipe of a closed circuit for the flow of the stock when the stock to the pressure head box is interrupted, said closed circuit consisting of a white water tank below the wire, a mixing pump, a valved stock inlet pipe for said mixing pump, a pipe extending to said mixing pump from the white water tank for guiding the contents of said tank to the mixing pump, a stock storage tank, a pipe extending from the mixing pump to the stock storage tank, a pressure pump for receiving stock from the storage tank and pumping the same through the head box pipe, a pipe connecting the storage tank and pressure pump, a stock supply cut off valve connected with said head box pipe, and a pipe connecting said white water tank with said stock supply cutoff valve, whereby upon the closure of the valved stock inlet pipe and the stock supply cutoff valve, the continued operation of the mixing and pressure pumps continues the flow of stock in said closed circuit without enriching the stock by a further supply of stock, to enable the supply of stock which will be fed upon the wire upon resumption of operation to be of substantially the same density, quantity and pressure of the stock at the wire as existed prior to the interruption which took place when said valved stock inlet pipe and said stock supply cutoff valve were closed.

2. In an apparatus for regulating and delivering paper stock to Fourdrinier paper-making machines having a wire, a stock pressure head box with a stock flow nozzle for supplying stock to the wire, and a stock supply pipe having one end thereof connected with the stock pressure head box, the combination with said head box of a closed circuit for the flow of the stock when the stock to the pressure head box is interrupted, said closed circuit consisting of a white water tank below the wire, a mixing pump, a valved stock inlet pipe for said mixing pump, a pipe extending to said mixing pump from the white water tank for guiding the contents of said tank to the mixing pump, a stock storage tank, a pipe extending from the mixing pump to the stock

storage tank, a pressure pump for receiving stock from the storage tank and pumping the same through the head box pipe, a pipe connecting the storage tank and pressure pump, a stock supply cutoff valve connected with said head box pipe, and a pipe connecting said white water tank with said stock supply cutoff valve, whereby upon the closure of the valved stock inlet pipe and the stock supply cutoff valve, the continued operation of the mixing and pressure pumps continues the flow of stock in said closed circuit without enriching the stock by a further supply of stock, to enable the supply of stock which will be fed

upon the wire upon resumption of operation to be of substantially the same density, quantity and pressure of the stock at the wire as existed prior to the interruption which took place when said valved stock inlet pipe and said stock cutoff valve were closed, a valved by-pass connection between the pipes leading to and from the mixing pump, a valved by-pass connection between the pipes leading to and from the pressure pump, whereby said closed circuit passes through the by-pass connection.
